(57) **CLAIM**

The ornamental design for a foam sandal, as shown and described.

DESCRIPTION

FIG. 1 is a front lateral perspective view of the foam sandal; FIG. 2 is a front medial perspective view of the foam sandal; FIG. 3 is a top view of the foam sandal; FIG. 4 is a medial side view of the foam sandal; FIG. 5 is a lateral side view of the foam sandal; FIG. 6 is a front view of the foam sandal; FIG. 7 is a rear view of the foam sandal; and, FIG. 8 is a bottom view of the foam sandal.

Only the portion of the foam sandal above the upper rim of the perimeter of the foot bed is claimed. The contour and shape of any portion of the sandal below the upper rim of the perimeter of the foot bed forms no part of the claimed invention. The broken lines are for illustrative purposes only and form no part of the claimed design.

The outsole tread texture as shown in FIG. 8 forms no part of the claimed invention.
